FOLDING UMBRELLA

Hans Haupt, Berlin-Zehlendorf, Germany

Application July 28, 1939, Serial No. 287,176
In Germany August 3, 1938

6 Claims. (Cl. 135—26)

My invention relates to improvements in folding umbrellas, and more particularly in umbrellas of the type in which the ribs comprise three telescoping sections, the median sections being freely movable on the inner rib sections and having the braces attached to their inner ends, and the outer and median rib sections being provided with locking means for holding the outer stick sections in extended positions, and in which the 5 inner rib sections are adapted to disengage said locking means when the ribs are being collapsed. One of the objects of the improvements is to provide an umbrella of this type in which the median and outer rib sections are uniformly moved inwardly and with their locking means into engagement with the inner rib sections, so that said locking means are simultaneously disengaged. This is important for the reason that the ribs might be injured if only one or a few of the outer 10 sections remain in locked position so that it must take up the whole pressure of the hand when the ribs are telescoped inwardly. In the preferred construction subsidiary braces and a subsidiary runner are provided which insure such uniform 15 movement of the median and outer rib sections.

For the purpose of explaining the invention an example embodying the same has been shown in the accompanying drawing in which the same reference characters have been used in all the 20 views to indicate corresponding parts. In said drawing:

Figs. 1 to 4 are elevations showing the frame of the umbrella respectively collapsed, extended and in two intermediate positions, Fig. 1 showing the 25 umbrella collapsed, Fig. 2 showing the same with the outer rib sections extended and the other parts collapsed, Fig. 3 showing the same in the position in which the handle and the outer stick member is further telescoped outwardly, and Fig. 40 4 showing the same in completely extended position, the dotted lines in Fig. 4 showing the frame in open position.

Fig. 5 is a detail sectional view on an enlarged scale showing the joint and the locking means of 45 the outer and median rib sections and the outer end of an inner rib section which is about to disengage the said locking means.

Fig. 6 is an elevation viewed from the left in Fig. 5, and

50 Fig. 7 is a sectional elevation showing a detail. In the construction shown in the figures the frame of the umbrella comprises a stick composed of telescopic members 1, 2 and 3, the stick member 3 being telescopically located within the stick member 2, and the stick member 2 being located

within the stick member 1. To the upper or inner stick member 1 a crown 4 is fixed which has the ribs jointed thereto. The said ribs comprise inner sections 5 and median outer sections 6 and 7, which are in telescopic engagement with one another. The upper or inner rib section 5 may consist of a solid rod and the median and outer rib sections 6 and 7 consist of rods which are U-shaped in cross section. The rib section 5 engages in the channel of the rib section 6, and the 10 rib section 6 engages in the channel of the outer rib section 7. The cover 8 of the umbrella is attached to the crown 4 and to both ends of the outer rib sections 7. To the inner ends of the median rib sections 6 braces 9 are jointed at 10 15 which are jointed with their other ends to a runner 15. The braces 9 have auxiliary braces 11 attached thereto, which are jointed with their other ends to an auxiliary runner 14 at 13. In the closed position of the umbrella shown in Fig. 20 4 the runner 15 is held by means of a spring latch 17 engaging in a slot 25 of the runner, and in the expanded position of the umbrella the runner 15 is supported on a spring latch 16. To the lower stick member 3 a handle 24 is secured. 25

To the inner or upper ends of the outer rib sections 7 sleeves 18 are fixed which are slotted at their opposite ends to provide spring latches 19 and 20, the said spring latches being bent inwardly and into positions for engaging in notches 30 21 and 22 made in the webs of the rib member 6, the said notches providing shoulders locking the sleeves 18 and the outer rib sections 7 in position on the median rib sections 6. The spring latches 19 prevent inward movement of the rib 35 sections 7, and the spring latch 20 prevents the said rib sections 7 from being pulled outwardly and out of engagement with the median rib sections 6. Similar latches 26 are provided at the inner ends of the median rib sections 6 for preventing outward movement of the said rib sections out of engagement with the rib sections 5. These spring latches have been shown in Fig. 7.

When the umbrella is collapsed from the position shown in Fig. 4 and into the position shown 45 in Fig. 3 the median rib sections 6 are telescoped inwardly on the rib sections 5, and there is practically no resistance to such inward movement, because there are not locking members preventing such inward movement of the rib sections, 50 and the auxiliary braces 11 do not exert pressure on the main braces 9, the said auxiliary braces 11 acting on the main braces 9 only when the umbrella is in the expanded position shown in Fig. 4 in dotted lines. Near the end of the in- 55

ward movement of the rib sections 6 the outer ends 23 of the rib sections 5 get into positions for engaging the spring latches 19, which thereby are pressed outwardly and out of engagement with the notches 21, the rib members 5 being preferably tapered at their outer ends. Thus the locking members 18 connecting the rib sections 6 and 7 are disengaged, so that also the outer rib sections 7 may be telescoped inwardly and into the positions shown in Fig. 1. It is important that all the spring latches 19 are simultaneously disengaged, because, if only one or two of the said spring latches are left in locking engagement their rib sections 7 would have to take up the whole axial pressure exerted on the outer rib sections 7 for telescoping the same inwardly, which pressure would break the ribs. In my improved umbrella the auxiliary braces 11 insure simultaneous and uniform inward movement of the rib sections 6 and therefore simultaneous disengagement of the spring latches 19, the said auxiliary braces being all jointed to the same runner 14 and always holding all the ribs in equal angular positions relatively to the stick.

25 Further when the outer rib sections 7 are telescoped outwardly from collapsed position into extended position the resistance to be overcome is but small, because at this time the cover is loose, the said cover being expanded only afterwards by the auxiliary braces 11 when the umbrella is opened.

When the closed umbrella is collapsed at first the inner rib sections and thereafter the outer rib sections are telescoped inwardly. When the umbrella is extended from the collapsed position shown in Fig. 1 the rib sections are telescoped outwardly in the reverse order, the outer ends of the outer rib sections 7 are pressed by the hand on the handle 24, and they are telescoped outwardly together with the outer stick member 3, until the locking members 18, 19, 21 are engaged, the rib sections 7 being prevented from being pulled out of engagement with the rib sections 6 by the spring pawls 20 engaging in the notches 22. This operation does not require much force because the cover of the umbrella is not stretched, and the rib sections 5, 6 and the stick members 1 and 2 do not take part in this operation, because the spring 17 is held by the stick member 2 in retracted position and out of engagement with the slot 25 of the runner 15. When the umbrella is further extended the spring 17 engages in the said notch 25, and thereafter the runner 15, the main braces 9, the auxiliary braces 11, the auxiliary runner 14 and the rib sections 6 are pulled outwardly.

I claim:

1. In a folding umbrella, a frame comprising a stick, ribs each comprising three telescoping sections, the inner and median rib sections being freely movable relatively to each other, a runner, braces jointed to said runner and to the inner ends of the median rib sections and adapted to hold the said median rib sections extended, means engaging said stick and braces adapted when the umbrella is open to hold said braces in posi-

tions for holding said median rib sections extended, and locking members adapted to hold the outer rib sections relatively to said median rib sections in extended positions, said locking members being in position for being disengaged by 5 said inner rib sections when the umbrella is being collapsed.

2. In a folding umbrella, a frame comprising a stick, ribs each comprising three telescoping sections, the inner and median rib sections being 10 freely movable relatively to each other, a main runner, main braces jointed to said main runner and to the inner ends of the median rib sections and adapted to hold the said median rib sections extended, a subsidiary runner, subsidiary braces 15 jointed to said subsidiary runner and to said main braces and adapted when the umbrella is open to hold said main braces in positions for holding said median rib sections extended, and locking members adapted to hold the outer rib 20 sections relatively to said median rib sections in extended positions, said locking members being in positions for being disengaged by said inner rib sections when the umbrella is being collapsed.

3. A folding umbrella as claimed in claim 1, 25 in which the said inner rib sections are telescopingly mounted within said median rib sections, and in which said locking members project into the paths of said inner rib sections and into positions for being thrown thereby into non- 30 locking positions.

4. In a folding umbrella, a rib comprising three telescoping sections, one formed near its end adjacent to another section with a shoulder, and a locking member in the form of a sleeve fixed 35 to the end of said other section and carrying a spring in position for locking engagement with said shoulder, said spring being in position for being disengaged from said shoulder by the rib section remote from said locking member and 40 shoulders.

5. In a folding umbrella, a stick, a rib comprising three telescoping sections, a locking device between the outer and median sections consisting of a sleeve carrying a spring nose and a notch, 45 said sleeve and notch being provided respectively on said outer and median sections, said spring nose being in position for being disengaged from said shoulder by the inner rib section.

6. A folding umbrella as claimed in claim 1, 50 comprising a stick made in telescoping sections, a handle on the outer stick section in position for having the outer ends of said outer rib sections assembled thereon, and a spring latch on the outer stick section for holding said runner when the umbrella is closed with the stick in extended 55 position, said spring latch being on its stick section in such position that when the collapsed umbrella is being extended with the said outer rib sections assembled on said handle it is held 60 by the median stick section in retracted position and released therefrom only when the said outer rib sections are substantially in the positions in which the said locking members are in positions for getting into locking engagement.
